UNITED STATES PATENT OFFICE

GERHARD HAEBLER, OF BRESLAU, GERMANY, ASSIGNOR OF ONE-HALF TO THEODORE HAEBLER, OF NEW YORK, N. Y.

SHEDDING MECHANISM FOR JACQUARD LOOMS

Application filed September 9, 1929, Serial No. 391,361, and in Germany September 13, 1928.

Various propositions have been put forward with the object of eliminating the disadvantages and cost of the known jacquard cards for weaving looms, but so far as I am aware the problem has not yet hitherto been 5 fully solved.

The object of the present invention is a means whereby jacquard cards will be rendered unnecessary for the shedding motion in 10 Jacquard and other looms or apparatus wherein jacquard card has hitherto been considered necessary, and according to the invention with this object in view, a design prepared in the manner of a drawing or the 15 like which may be photographically reduced is used in combination with a light sensitive cell, which may be of any known type, selenium or other, to close or to leave open electric circuits for the movement or otherwise 20 of the cords and mails of the jacquard harness, as relative movement of the drawing and the cell takes place point by point of the said drawing to present a light or dark point of the latter to the cell.

With such an arrangement all the cords of 25 a Jacquard loom, which are to be lifted, may be lifted rapidly and the pick then takes place, the whole operation of shedding being so rapid that the loom may be operated to its 30 full speed capacity. If for instance the speed is to be two picks per second, and there are n mails to the loom, then every point of the drawing which takes the place of a jacquard card may affect the sensitive cell at the longest 35 for $1/2 n$ of a second for the purpose of registering a fluctuation by the light sensitive cell for that time.

For a Jacquard loom with 500 mails and 40 two picks per second, then, for every point in the drawing there is required one-thousandth of a second of time in which the registration takes place of such point by the sensitive cell. The short current impulses of the 45 sensitive cell may be strengthened by known means in order to operate relays which by means of magnets will lift or repel the cords of the harness, as required.

The invention may be carried out in two 50 divisions if desired, the first part consisting in registering light or dark points of the pat-

tern drawing and for instance magnetizing accordingly a moving steel band, wire or the like which in its turn will move between or past induction coils which will actuate through current reinforcing means and magnets the jacquard harness. The band or the like is in this case a pattern card having the jacquard lifting design magnetized upon it. 55

Poulsen many years ago showed the way in this, that a steel wire or steel band could be magnetically influenced in varying degrees as it moved past a magnet or magnets, and that by subsequently moving the band or wire adjacent to induction coils varying degrees of current could be obtained according to the strength of magnetization of the band or wire at various points, to operate for instance a telephone transmitter as often as desired to repeat vibrations which through magnets originally magnetized the band or wire. This system I can utilize for my purposes in one form of my invention, viz: the formation of a pattern card for use in a Jacquard loom. 60 65 70

The invention will now be described fully 75 by way of example in the forms at present best known to me, reference being had to the accompanying drawings which are schematic. The illustration of details of construction of magnets, current reinforcing means and so 80 on is considered unnecessary, as these are well known.

In the drawings:—

Fig. 1 is a diagram of the apparatus provided with a light sensitive cell which is 85 slideable. Fig. 2 is a diagram showing a modification of the apparatus provided with a stationary light sensitive cell.

Figures 3 and 4 are further schematic views, to illustrate respectively the preparation and the application of a steel band having the pattern design magnetized thereon; and Figure 5 is a detail showing the use of a light cell. 90 95

It may be stated first in reference to this Figure 5 that s is a pencil of light the rays of which pass through a hole t in a cell m covered with flat plates of selenium u as seen in the figure, the rays falling on the drawing on which the pattern has been prepared, and 100

which drawing will be hereinafter called the pattern. From the latter the rays are reflected as shown, on the selenium surfaces.

Referring now to Figure 1, for each cord *e* or the like *e* in the loom harness there is provided an electro-magnet *d* and a relay of suitable form *c*. In the instant that any point of the pattern on *a* is illuminated to affect the light sensitive cell *m* a current reinforcing mean *g*, of any convenient construction, is put in circuit with the corresponding relay *c* of the cord *e* which is affected by that particular point of the pattern. An electric battery 12 is connected with all the electromagnets *d* by a lead 14 having an automatic circuit breaker *i*, and is connected to the relays *c* by leads 15. The relays *c* are connected with the reinforcer *g* by a lead 15'. The reinforcer may also be an electric battery, and it is connected with the sliding contact member *f* by a lead 16, and with the light sensitive cell *m* by leads 17 and 18. Each relay *c* is provided with a stationary contact *f'* which serves to transmit current from the reinforcer *g* to an appropriate relay *c* when the sliding contact *f* comes in contact with the stationary contact pertaining to such relay, and the circuit is closed. The circuit is not closed however unless completed by the light sensitive cell *m*. The movement of the sliding contact member *f* is effected by any suitable crank plate 20 and connecting rod 21, and the light *b* and the light sensitive cell *m* are moved with the contact member *f*. The drum *a* which carries the pattern in light and dark spots or points is rotated from time to time, to vary the pattern, by any approved means. In Fig. 2 the corresponding parts are arranged in a different way, and the light *b* and the light sensitive cell *m* are stationary. The drum *a'* is rotated to correspond with the movements of the contact *f*, and the drum is moved longitudinally from time to time to vary the pattern.

It may be here noted, that pattern points of varying shades need not be considered, as any point is either positively a part of the design or is a blank space thereof, and it follows therefore that a cord *e* is either lifted or not lifted. As soon as the various cords *e* are in their positions as affected by the movement of the pattern and the operation of the relays *c* and magnets *d*, these operations taking the fraction of a second, the pick takes place and through an automatic circuit breaker *i*, Figure 1, all the relays and magnets are then returned to their first condition for the next pick, for which next pick the pattern moves on.

I do not bind myself to the use of any special type of sensitive cell, as any known in electro-technics may be used, for instance the diffuse reflex type or the known form in which a reflector glass is used.

The "feeling" of the pattern may be ef-

fected in various ways, either by moving the sensitive cell past the pattern; or by moving the pattern past the sensitive cell; or by moving both in opposite directions in relation to each other.

The pattern, according to the example of construction which I am now describing, is placed on a drum, the light being thrown upon a pattern point, as shown in Figure 1. Any other form of bearer for the pattern may be employed however to achieve the object desired.

It is to be expressly noted that for every cord *e* an electromagnet *d* is provided, as well as a relay *c*, whilst the current reinforcer *g* can serve generally for all relays together with a sliding contact *f*.

The points of the pattern which are to be affected may be in groups for one and the same pick, as will be understood, with the provision of a plurality of cells and light pencils. A very high speed may be thus attained as each pencil of light may thus only affect a limited number of pattern points.

In carrying out the invention it will be seen that with the help of the desired apparatus a film, wire, steel band, roller, plate or other device may be electrically, magnetically or mechanically so influenced or altered that by means of any of these latter intermediaries the actual movement of the cords *e* of the harness may be effected according to the pattern. The whole arrangement would in that arrangement be in two parts, or divisions, as will be seen later, viz: electrical preparation of a "card", and the use of this card for effecting the loom shedding.

The card may form a very cheap and efficient substitute for the usual costly jacquard card.

Fig. 3 shows a means for forming the pattern on a steel band 1. The electric impulses from the battery or reinforcer *g* are used to energize electromagnets *k* to which the reinforcer is connected by leads 24 and 25. These electromagnets *k* are caused to magnetize the steel band 1, which passes over rollers *n* which are rotated by any approved means. The surface of the band 1 is magnetized in spots or points by induction, and as it is moved at a constant speed in synchronism with the movements of the light sensitive cell and sliding contact member *f*, a pattern is formed on the band.

In Fig. 4 the band is shown in operation. The magnetized spots or points on the band passing between the electromagnets *k* cause fluctuations in the current which passes to the relays *c*, as hereinbefore described with respect to Fig. 1. Additional electromagnets *k'* are also provided, and are similar to the electromagnets *k*. These additional electromagnets are operatively connected with an additional reinforcer or battery *g'* and a sliding contact member *f*. These parts

operate to ensure a perfect registration of the pattern magnetized on the band 1 with the original pattern on the drum. The slideable contact member *f* is driven by any approved crank and connecting rod as hereinbefore described.

Between each pick of the loom, all the relays *c*, all the electromagnets *d*, and all the jacquard cords *e*, are controlled in regular order by the contact member *f*, and whether or not a cord is operated depends upon whether or not current is passed into the relay pertaining to it by the contact member *f*. This in turn depends upon the initial impulse or variation imparted to the current, when the circuit is closed by the light sensitive cell *m*, and this in turn is due to the lightness or darkness of the spots or points which form the pattern.

20 I claim:—

1. In a jacquard operating device, a series of jacquard cords, a separate electric magnet for operating each cord, a relay connected to each electromagnet and having an electric contact, a contact member, means for placing the said contact member in electric engagement with all the contacts of the relays one after another in regular order between each pick of the loom, an electric circuit connecting all the electromagnets and relays with the said contact member, and means for varying the current in the said circuit according to a predetermined pattern as each relay is placed in regular order in electric engagement with the said contact member, the electromagnets being thereby energized more or less, and in regular order, and the cords being operated according to the pattern.

2. A jacquard operating device as set forth in claim 1, the said means for varying the current comprising a travelling steel band magnetized in spots or points of its length to form a predetermined pattern, the spots or points being in separate series arranged one after another, each series corresponding to the contact members of the relays, and electromagnets arranged one on each side of the said band and included in the said circuit and operating to vary the current to the relays one after another in regular order and according to the patterns on the steel band.

3. In a jacquard operating device, a series of jacquard cords, an electric circuit provided with a series of electric devices for operating each jacquard cord independently of the others, each said electric device being provided with a separate electric contact, a contact member slideable to make contact with the said electric contacts one after the other in regular order, a pattern having light and dark spots or points, a light sensitive cell included in the electric circuit and controlled by the said pattern and secured to the contact member to move therewith, and means for sliding the said contact member and light

sensitive cell relatively to the said pattern and electric contacts.

4. A jacquard operating device as set forth in claim 1, the said means for varying the current comprising a pattern having light and dark spots or points, and a light sensitive cell included in the said circuit and controlled by the said pattern, the said pattern and cell being movable with respect to each other and being timed to correspond with the periodic action of the contact member upon the electric contacts.

In testimony whereof I have hereunto set my hand.

GERHARD HAEBLER.
